(57) **CLAIM**

The ornamental design for a controlled document tracking and/or authentication device, as shown and described.

DESCRIPTION

FIG. 1 is a front perspective view of a controlled document tracking and/or authentication device in accordance with a first embodiment of my design;

FIG. 2 is a front elevation view thereof;

FIG. 3 is a rear elevation view thereof;

FIG. 4 is a a is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a front perspective view of a controlled document tracking and/or authentication device in accordance with a second embodiment of my design;

FIG. 10 is a front elevation view thereof;

FIG. 11 is a rear elevation view thereof;

FIG. 12 is a a is a left side view thereof;

FIG. 13 is a right side view thereof;

FIG. 14 is a top plan view thereof;

FIG. 15 is a bottom plan view thereof;

FIG. 16 is a rear perspective view thereof; and,

FIG. 17 is the view from FIG. 1, with an example passport affixed thereto to demonstrate unclaimed environment.

The broken lines represent environmental structure and form no part of the claimed design. The dotted lines represent the boundary between unclaimed and claimed subject matter and form no part of the claimed design.

It will be appreciated that the controlled document tracking and/or authentication device may be used in connection with a controlled document such as, for example, a passport, visa document, identity card, and/or the like.

1 Claim, 13 Drawing Sheets
